UNITED STATES PATENT OFFICE.

SILAS E. BUTLER, OF TOLEDO, OHIO.

CARTON.

Application filed July 15, 1925. Serial No. 43,673.

This invention relates to cartons used for packaging butter, oleomargarine and the like, but more particularly relates to devices for maintaining the cartons in folded relation.

5 Objects of this invention are to provide a simple and inexpensive device for holding the end flaps of a carton in folded position; and to provide frictional means associated with the end flaps for preventing unfolding 10 thereof.

The invention is shown for purposes of illustration in the accompanying drawings in which,—

Fig. 1 is a side elevation of the carton 15 with the flaps in unfolded or extended position; Fig. 2 is a section on the line 2—2 of Fig. 1; Fig. 3 is a perspective view of the carton; and Fig. 4 is an end view of the carton with the side closure flaps in folded 20 position.

The illustrated embodiment of the invention comprises a carton having side panels 1, 2, 3 and 4 and the panel 2 is provided with a marginal extension 5 which is 25 folded inwardly and is adhesively attached to the inside of the panel 3. Formed on the opposite ends of the panel 1 are side closure flaps 6 and 7 which correspond respectively with the side closure flaps 8 and 9 on the 30 ends of the panel 3. On one end of the panel 2 is an end closure flap 10 having a transversely foldable insertion lip 11, and at the opposite end of the carton an end closure flap 12 is provided on the panel 4 35 and terminates at its outer end in a foldable insertion lip 13.

It has been found in the sealing of cartons of the above character that the end panels do not remain in folded position, and 40 this is particularly true in the case of a flap such as 12 which is away from the adhesively connected extension 5. The reason for such unwarranted unfolding is especially because the extension 5 is not always fastened to the panel 3 in such a manner 45 that a comparatively small space is provided between the edge of the side flap 8 and the panel 2. If the space therebetween is relatively large, then there is not a sufficient frictional binding action to hold the end closure flap 12 in folded relation, in other words a variable opening is formed according to the sealing operation of the sealing machine. It will be apparent that 55 this problem is not present as regards the end flap 10 because the panels 1, 2 and 4 are

of one piece and this flap is connected to the panel 2 in the region of the extension 5.

In order to overcome the above objection and effect a reliable holding of the flap 12 60 in folded position, an extension tip 14 is provided on the marginal extension 5, preferably integral therewith. As shown, the tip 14 may be pointed with outer edge tapering inwardly and is adhesively secured to the inner face of the side flap 8. It will be apparent that when the flaps 8 and 6 are folded together the space for receiving the foldable lip 13 is 65 constant irrespective of the irregularity in 70 the sealing of the marginal extension 5. This space is sufficient to bind the lip 13 frictionally in place so that accidental unfolding is prevented. To facilitate the insertion of the lip 13, a notch 15 may be cut 75 out of the flap 8 although this is optional and is not essential in every instance.

While I have shown and described a construction which is the best form known to me at the present time it is to be understood 80 that numerous changes in details of construction and arrangement may be effected without departing from the spirit of the invention, especially as defined in the appended claims.

What I claim as new and desire to secure by Letters Patent, is—

1. A carton formed from a one-piece blank providing when folded a plurality of side walls, a marginal extension on one 90 wall adhesively connected to the inside of an adjacent side wall, oppositely positioned side closure flaps, and an end flap, a foldable lip on said end flap, and an extension strip on said marginal extension attached to the 95 inside of the adjacent side closure flap whereby when inserted inside the carton said lip frictionally engages said strip to prevent accidental unfolding of the end flap.

2. A carton having four sides foldably connected together, and a sealing strip at the outer edge of one side adapted to marginally lap and be sealed to the adjacent edge of an adjoining side, side flaps hingedly secured to the ends of opposite sides, end 100 closure flaps hinged to opposite ends of opposed sides other than the sides to which the side flaps are secured and each having an insertion tongue at its free end, the insertion tongues adapted to be inserted into the body 105 of the carton between a side of the carton and edges of the adjacent side flaps, and a 110

tapered extension on one end of the sealing strip foldable transversely with respect to the carton body and adapted to cooperate with the adjoining carton side to form a space for the insertion of the adjacent end closure lip, which space before and after the shaping of the carton is constant in size for the insertion of the lip.

3. A one-piece carton having four sides, 10 a marginal extension on one side overlapping and adhesively connected to an adjacent side, side flaps foldably connected to opposite sides, an end flap on the side opposite from the side provided with said marginal extension, an insertion lip on said end flap, and an extension tip on said extension flap whereby when folded said extension tip

engages said lip for holding the latter in folded relation.

4. A one-piece carton having four sides, a marginal extension on one side overlapping and adhesively connected to an adjacent side, side flaps foldably connected to opposite sides, an end flap on the side opposite from the side provided with a marginal extension, and an insertion lip on said end flap, and an extension tip on said marginal extension overlapping an adjacent side flap, said tip having an inclined outer edge 25 to cooperate with that side having said marginal extension for holding said insertion lip in folded relation.

In testimony whereof, I have hereunto signed my name to this specification.

SILAS E. BUTLER.
